(57) **CLAIM**

The ornamental design for a cap of packaging container as shown and described.

DESCRIPTION

FIG. 1 is a perspective view of a cap of packaging container showing my new design, which includes a central bulge having a vertical strip pattern with a lot of grooves; FIG. 2 is a front view thereof;

FIG. 3 is a rear view thereof;

FIG. 4 is a top plan view thereof;

FIG. 5 is a bottom plan view thereof;

FIG. 6 is a right side view thereof;

FIG. 7 is a left side view thereof;

FIG. 8 is a sectional view taken along line 8-8 of FIG. 4; and, FIG. 9 is a sectional view taken along line 9-9 of FIG. 4. The thin lines of each figure indicate three-dimensional surfaces of the cap of packaging container of my new design.
